UNITED STATES PATENT OFFICE.

EMIL L. CLAUS, OF MILWAUKEE, WISCONSIN.

COMBINED BURNER STRUCTURE FOR GAS-STOVES.

1,395,799.

Specification of Letters Patent.

Patented Nov. 1, 1921.

Application filed March 21, 1919. Serial No. 284,103.

To all whom it may concern:

Be it known that I, EMIL L. CLAUS, a citizen of the United States, and resident of Milwaukee, in the county of Milwaukee and State of Wisconsin, have invented certain new and useful Improvements in Combined Burner Structures for Gas-Stoves; and I do hereby declare that the following is a full, clear, and exact description thereof.

10 My invention relates to new and useful improvements in gas burning apparatus more particularly of that type embodied in domestic cooking stoves.

Such cooking stoves are usually provided 15 with a plurality of main burners and a relatively small simmering burner adapted to supply a small amount of heat for certain cooking operations. In addition to economy of manufacturing costs, a very important 20 consideration in commercial structures of this character resides in the amount of space taken up within the confines of the stove by the burners and their valve connections with the supply pipe extending along the front 25 of the stove. When a considerable number of burners are employed in connection with a simmering burner, it is difficult to procure a desired spaced relation of the supply valves for the various burners.

30 It is therefore primarily the object of my invention to combine the structure of the simmering burner with the structure of one of the main burners of the stove, to procure economy in manufacturing costs and to 35 also procure an increased free space within the desired confines of the stove. More particularly, it is an important object to combine the control means for both the main and simmering burners in a single valve 40 structure, to thus reduce the number of valve units along the main supply pipe of the stove, permitting an increased freedom of manipulation of the valve and lessening the danger incidental to accidental opening of 45 the valves.

A further object resides in the provision 50 of an arrangement wherein the simmering burner and one of the main burners of the stove may be embodied in a single casting to thus avoid the necessity of providing an additional casting for the simmering burner, and to procure an economy of space which would otherwise be occupied by the simmering burner.

55 A still further object resides in the provision of a valve structure which is oper-

ative to supply gas to either the simmering burner or its associated main burner, and which in certain instances may be manipulated to supply gas simultaneously to both 60 burners.

In my co-pending application for patent, means is disclosed for automatically actuating igniter torches for selective burners upon opening the supply valves for such 65 burners. In this connection it is a still further object to automatically actuate an igniter torch for both the simmering and main burners when the combined valve structure is operated to supply gas to either of said 70 burners.

With the above and other objects and advantages in view, which will be apparent as the description proceeds, my invention resides in the novel features of construction, 75 combination and arrangement of parts as hereinafter more particularly described and defined by the appended claims.

In the accompanying drawings:

Figure 1 is a plan view of a combined 80 main burner and simmering burner structure embodying my invention.

Fig. 2 is a vertical sectional view through the valve structure on a plane indicated by the line 2-2 of Fig. 1.

Fig. 3 is a horizontal sectional view 85 through the valve structure on the line 3-3 of Fig. 2.

Fig. 4 is a horizontal sectional view 90 through the valve structure on the general plane of the torch ports, as indicated by the line 4-4 of Fig. 2.

Fig. 5 is a vertical sectional view through the valve structure on a plane at right angles to the plane of Fig. 2, as indicated by the 95 line 5-5 of Fig. 2.

Fig. 6 is an elevational view of a modified valve structure.

Fig. 7 is a sectional view through said 100 valve structure on the line 7-7 of Fig. 6.

Fig. 8 is a sectional view through said valve structure on the line 8-8 of Fig. 6.

Fig. 9 is a sectional view through said 105 valve structure on the line 9-9 of Fig. 6.

Fig. 10 is a sectional view through said valve structure on the line 10-10 of Fig. 6.

Fig. 11 is a plan view showing a modified 110 main and simmering burner structure.

Referring now more particularly to the drawings, 5 designates the usual supply pipe which is disposed along the front of an ordinary domestic gas stove, and in carrying out

2
my invention, a single valve casing 6 has its inlet portion 7 threaded in the pipe for supplying both the main burner and the simmering burner.

5 As shown in Fig. 1, these burners are preferably embodied in a single casting comprising the usual duct 8 for conveying commingled air and gas, this duct being enlarged in substantially cup shape to form
10 the mixing head 9 adjacent the valve, and having its other end merged into and communicating with the hollow annular burner head 10 having radial fins 11 provided with the burner jet openings. In carrying out
15 my invention, the duct 8 is provided preferably adjacent one side with a longitudinal partition 12, which is extended into the burner head and directed laterally to cut off the adjacent fin, designated specifically at
20 11^a, from the major portion of the burner head. This partition is also extended into the mixing head 9 to divide off a corresponding portion of said mixing head. The valve casing is provided with a main discharge
25 nipple 13 projecting centrally into the mixing head 9 in the usual manner, and has a lateral extension 14 from which a nipple 15 extends for projection into the portion of the mixing head divided off by the partition 12. The usual control valve plate 16 is rotatably mounted on the end of the air
30 mixing head 9, being apertured at 17 to expose the mouth of the divided off portion of the head in the various adjusting positions of the valve plate.

35 Thus, when gas is supplied through the main burner nipple 13, it will mix with air in the head 9 and pass through the major division of the duct 8 for ignition at all of
40 the jets of the burner head with the exception of the jets of the fin or portion 11^a. When gas is supplied to the simmering supply nipple 15, it will mix with a sufficient quantity of air and pass through the minor division of the duct 8 for ignition at the jet
45 of the fin 11^a to thus supply sufficient heat for the desired purposes of a simmering burner. It is noted that the passageway of the divided off portion of the duct 8 is
50 slightly enlarged within the burner head to facilitate proper admixture of air with the gas.

55 Describing now the valve structure shown specifically in Figs. 2 to 5, it is noted that the valve casing 6 is provided with a torch supply port 18, preferably located under the simmering supply extension 14, and connected by a tube 19 with a torch head 20 preferably of the type shown in my said
60 copending application for patent, this torch head being adapted to direct a torch toward the burner head to ignite either the main burner or simmering burner section thereof. The usual slightly tapered valve member
5 or key 21 is rotatably mounted in the casing,

being held in seating position by a spring 22 coiled on its lower projected end portion and exerting pressure against the bottom of the casing 6 and against a washer secured by a screw 23 threaded in the lower portion 70 of a well 24, extending through the major portion of the valve member, the lower portion of the well being shouldered to seat a disk 25 of lead or other packing material whereby to effectively seal the lower portion 75 of the well. The inlet port 26 of the valve casing is inclined upwardly in the portion 7, while the main burner supply port 27 is inclined downwardly in the discharge nipple 13, said ports thus communicating with the 80 valve member at different elevations, and the valve member is provided at said elevations with passages 28 communicating with the well whereby when the ports and passages are in registry, free flow of gas will be 85 provided through the valve for the main burner, movement of the valve to effect this open position being procured in the usual manner, wherein the handle 29 of the valve member is swung in a clockwise direction 90 from a closing position substantially parallel to the main supply pipe 5 to a position wherein the handle member extends transversely of the supply pipe, this open position of the valve for the main burner being 95 illustrated in the drawing. The valve member is also provided with a torch supply passage 30 communicating with its well at the plane of the torch supply port 18, whereby as set forth in my said co-pending application for patent, a torch flow of gas will 100 be procured for the torch head upon movement of the valve member slightly past open position for the main burner. The valve casing is also provided with bypass ports 105 31, controlled by a valve screw 32, for supplying pilot flow of gas to the torch head.

110 Gas is supplied to the simmering burner extension 14 through a passage 33 communicating with the well at the plane of said extension, the valve being rotated from closed position in a counter-clockwise direction to procure registry of this passage 33 with the extension 14. A torch flow of gas upon this 115 registry is procured by a passage 34 extending oppositely from the passage 30 of the valve member in the plane of the torch supply port 18, the valve member being rotated slightly past its open position for the simmering burner to effect this torch flow.

120 An exceedingly simple and readily operated valve structure has thus been provided whereby upon turning the handle in one direction from a closed or neutral position, the main burner will be supplied with gas and ignited, and upon turning the handle in the other direction from closed or neutral position, the simmering burner will be supplied with gas and ignited, a slight retrograde movement of the valve member in either in- 125 130

stance serving to shut off the torch flow of gas and maintain full supply of gas to either burner. It is noted that the various ports of the valve structure are adapted for registration in four different planes, whereby accidental registry of the ports is avoided, and by disposing the main burner passages 28 of the valve member in the two intermediate registering planes, undesired registry of said members is prevented when the valve member is swung to torch supply position for the simmering burner.

In Figs. 6 to 10, a modified valve structure is shown wherein the various supply operations are more distinct, to lessen the possibility of accidental opening of undesired ports, and also to provide for simultaneous supply of gas to both the main burner and the simmering burner. In this structure, 20 the inlet port 26^a and the main burner port 27^a are disposed in a common intermediate plane, the simmering supply port 14^a and flash supply port 18^a being disposed respectively above and below said common plane. 25 A tapered valve sleeve 35 is rotatable in the valve casing, and the main valve member or key 21^a is rotatable in this sleeve, being provided with a well 24^a as heretofore described. The main valve member is provided in its 30 intermediate portion with opposed passages 36 communicating with its well and adapted to align with the ports 26^a and 27^a, and the valve sleeve is provided with passages 37 also adapted to register with the ports 26^a 35 and 27^a, whereby when all of the ports and passages are in registry, flow of gas is provided for the main burner. The valve sleeve is also provided with a passage 38 adapted to register with the inlet port 26^a and with a 40 passage 39 adapted to register with the simmering port 14^a, together with a passage 40 in the upper portion of the valve member. The valve member 21^a is provided with a handle 29^a, and the valve sleeve is provided 45 with a handle 41 movable in a plane under the first named handle.

The drawings illustrate the open position of the valve for the simmering burner alone, in this position the handles 29^a and 41 extending transversely of the supply pipe. The valve sleeve in this position shuts off the main burner port 27^a, the inlet port 26^a being open by registry of the sleeve passage 38 and the passages 39 and 40 are in registry 55 with the simmering supply port 14^a. In the closed position of the valve whereby, as is usual in gas stoves, the handles project substantially parallel to the main supply pipe 5, the opposed passages 37 of the valve 60 sleeve are disposed in registry with the main ports 26^a and 27^a, but the passages 36 of the valve member 21^a are disposed out of registry. Thus, to procure flow of gas to the main burner alone, it is merely necessary to 65 grasp the handle 29^a and swing the valve

member in a clockwise direction to a position transverse of the supply pipe, it being noted that upon turning movement of the valve member, the sleeve will remain stationary by reason of the differential peripheral areas of 70 the valve member and sleeve.

To procure torch flow of gas in connection with these aforescribed valve movements, the lower portion of the valve member is provided with a passage 42 adapted to register with the torch supply port 18^a when the valve member is swung slightly past its full registering position with the main valve. The valve sleeve is also provided with passages 43 which register with the torch supply port 18^a when the sleeve is in full closing position of the valve or in a position 80 of the valve which supplies the simmering burner alone.

Although the present valve is capable of 85 other use as will be later described, it is desired to point out that by the afore described structure, I have provided an arrangement wherein opening movement for supplying either the main burner or the 90 simmering burner may be procured by rotating either one or both of the handles through a substantially quarter rotation and in the conventional clockwise direction, it being noted that the controlling movement 95 for supplying the main burner is carried out in entirely conventional manner.

The present valve structure embodies also an arrangement for supplying gas simultaneously to both the main burner and 100 the simmering burner, and to this end, the valve sleeve is provided with a port 44 which is adapted to register with the simmering supply ports 14^a when the valve sleeve is rotated through a half-circle 105 from its full closing position, and the sleeve is also provided with a passage 45 adapted to register with the torch supply port in this position of the sleeve. Hence, when the sleeve is swung to this extreme position, it 110 affords free passage through all of the ports of the valve and when the valve member is swung to open position, gas is supplied through the main and simmering ports 115 and may also be supplied through the torch supply port. The valve sleeve is limited to swinging movement through a half-circle by a pin 46 carried thereby and engageable with stop shoulders 47 on the valve casing.

In some instances, it may be desirable to 120 space the simmering burner from the main burner, and the structure shown in Fig. 11 may be employed, wherein the main burner occupies the entire expanse of the burner head 48, and wherein a simmering burner 125 head 49 is carried by a pipe 50 which is threaded in a boss 51 on the supply duct 52 of the main burner head, said supply duct being provided with a longitudinal partition 12^a defining a passageway communi- 130

cating with the pipe 50 and with the sim-
mering supply nipple 15 of the valve.

While I have shown and described pre-
ferred embodiments of various phases of
5 my invention, to meet differing desired con-
ditions of use, it will be appreciated that
still other embodiments involving various
changes and modifications of structure may
be employed to meet other conditions of use
10 and manufacture without departing in any
manner from the spirit of my invention as
defined by the accompanying claims.

What is claimed is:

1. A structure of the class described in-
cluding a main burner portion, a simmerring
burner portion, a torch head adapted to
direct a torch for igniting gas at either

the main burner or the simmerring burner
portion, a single valve adapted to supply gas
to either the main burner or the simmerring 20
burner, and means for supplying the torch
head with torch flow of gas upon supply
of gas to either burner portion.

2. In a structure of the class described, a
main burner, a simmerring burner, a torch 25
head in alinement with said burners, and
adapted to light either, and a valve movable
selectively to supply gas simultaneously to
the torch head and either one of the burners.

In testimony that I claim the foregoing I 30
have hereunto set my hand at Milwaukee, in
the county of Milwaukee and State of Wis-
consin.

EMIL L. CLAUS.
